(57) **CLAIM**

The ornamental design for an architectural metal building panel, as shown and described.

DESCRIPTION

FIG. 1 is an upper left front perspective view of an architectural metal building panel showing my new design in accordance with a first embodiment of the present invention; FIG. 2 is a left side view thereof; FIG. 3 is a front view thereof;

FIG. 4 is an upper left front perspective view of an architectural metal building panel showing my new design in accordance with a second embodiment of the present invention; FIG. 5 is a left side view thereof; FIG. 6 is a front view thereof;

FIG. 7 is an upper left front perspective view of an architectural metal building panel showing my new design in accordance with a third embodiment of the present invention; FIG. 8 is a left side view thereof; FIG. 9 is a front view thereof;

FIG. 10 is an upper left front perspective view of an architectural metal building panel showing my new design in accordance with a fourth embodiment of the present invention; FIG. 11 is a left side view thereof; and, FIG. 12 is a front view thereof.

The evenly broken lines in FIGS. 1-12 depict portions of the architectural metal building panel that form no part of the claimed design. The dash-dot-dash lines depict the boundaries of the architectural metal building panel and form no part thereof.

1 Claim, 8 Drawing Sheets
